DESIGN FOR A COMBINED BED TABLE AND REFUSE RECEPTACLE SUPPORT

Travis O. Smith, Kansas City, Mo., assignor, by mesne assignments, to David M. Lorenz, Johnson County, Kans.

Application February 7, 1944, Serial No. 112,499

Term of patent 7 years

(Cl. D33—14)

To all whom it may concern:

Be it known that I, Travis O. Smith, a citizen of the United States, residing at Kansas City, in the county of Jackson and State of Missouri, have invented a new, original, and ornamental Design
for a Combined Bed Table and Refuse Receptacle Support, of which the following is a specification, reference being had to the accompanying drawing, forming a part thereof.

Fig. 1 is a top perspective view of the combined bed table and refuse receptacle support, showing my new design; and

Fig. 2 is a bottom perspective view thereof.

I claim:

The ornamental design for a combined bed
table and refuse receptacle support, as shown.

TRAVIS O. SMITH.
